US0D1074773S

(12) **United States Design Patent** (10) **Patent No.:** **US D1,074,773 S**
(45) **Date of Patent:** **** May 13, 2025**

(54) **MOVABLE BARRIER OPERATOR**

(71) Applicant: **The Chamberlain Group LLC**, Oak Brook, IL (US)

(72) Inventors: **Jeremy Abel**, West Dundee, IL (US); **Matthew James Baer**, Forest Park, IL (US)

(73) Assignee: **THE CHAMBERLAIN GROUP LLC**, Oak Brook, IL (US)

(**) Term: **15 Years**

(21) Appl. No.: **29/981,845**

(22) Filed: **Jan. 2, 2025**

Related U.S. Application Data

(60) Continuation of application No. 29/954,890, filed on Jul. 30, 2024, which is a division of application No. 29/937,125, filed on Apr. 12, 2024, now Pat. No. Des. 1,052,620, which is a division of application No. 29/911,223, filed on Aug. 30, 2023, now Pat. No. Des. 1,023,069, which is a division of application No. 29/725,280, filed on Feb. 24, 2020, now Pat. No. Des. 1,013,735.

(57) **CLAIM**

The ornamental design for a movable barrier operator as shown and described.

DESCRIPTION

FIG. 1 is a first perspective view of a movable barrier operator;

FIG. 2 is a second perspective view thereof;

FIG. 3 is a bottom plan view thereof;

FIG. 4 is a top plan view thereof;

FIG. 5 is a first end elevation view thereof;

FIG. 6 is a second end elevation view thereof;

FIG. 7 is a first side elevation view of the movable barrier operator; and,

FIG. 8 is a second side elevation view thereof.

Broken lines in the drawings form no part of the claimed design.

1 Claim, 4 Drawing Sheets
